Attorney

UNITED STATES PATENT OFFICE.

ALBERT STEINER, OF TROY, MONTANA.

CONDIMENT HOLDER.

Application filed December 10, 1926. Serial No. 153,811.

My present invention relates to improvements in condiment holders adapted for containing and dispensing a plurality of seasoning elements, as pepper and salt. The 5 holder is designed to be inverted for use, and is provided with a plurality of compartments and a rotatable head having a perforated portion, and designed for selective use with the compartments.

10 Means are provided for rotating or oscillating the perforated head to selected position, and the device as a whole is simple in construction and operation and presents a neat and attractive appearance.

15 The invention consists in certain novel combinations and arrangements of parts as will hereinafter be more fully set forth and claimed.

In the accompanying drawings, I have 20 illustrated one complete example of the physical embodiment of my invention wherein the parts are combined and arranged according to the best mode I have so far devised for the practical application 25 of the principles of my invention.

Figure 1 is a view in elevation of a pepper and salt shaker embodying my invention;

Fig. 2 is an enlarged detail vertical sectional view at line 2—2 of Fig. 1;

30 Fig. 3 is a plan view of the holder at line 3—3 of Fig. 2; and

Fig. 4 is a transverse or horizontal sectional view at line 4—4 of Fig. 3.

In the preferred form of my invention, I 35 utilize a holder 1 of metal or other suitable material, and preferably tapered with a larger end forming the base or bottom. A closure 2 is used at the base of the holder, and this closure is in the form of a circular plate 40 inset within the lower end of the holder and removable therefrom in order to fill the holder with the pepper and salt, or other condiments. The bottom or closure 2 is provided with an annular flange 3 which is exteriorly threaded and screwed into the opening at the bottom of the holder, and the edge 4 of this flange is curled over or curved to fit over the edge of the holder and form a support for the device.

45 At the smaller end of the holder, I provide an oscillatable head 5 and one-half of the area of this head is perforated, the perforations being indicated at 5' in Fig. 3. This head is in the form of a circular plate 50 to close the smaller end of the holder and it is retained in an annular flange 6 which

forms a groove 7 at the edge of the holder for the reception of the circular edge of this oscillatable or rotatable head.

The holder is longitudinally divided by 60 a centrally located partition 8 and two compartments as 9 and 10 are thus formed in which two condiments as pepper and salt may separately be contained.

Through the longitudinal center of the 65 holder, a tubular stem 11 extends, this stem being elliptical in cross section and located at the center of the partition 8, an annular shoulder 13 is formed at the base of the stem 11, as seen in Fig. 2. Within the tubular 70 stem, a plunger 14 is reciprocable, and non-rotatable. This plunger also is of tubular formation, and is provided with a reduced push pin 15 which projects through an opening 16 in the holder bottom 2, and a shoulder 75 17 on the plunger bears against the bottom 2 of the holder as seen in Fig. 2.

At the upper end, the plunger is provided with a reduced pin portion 18 and a shoulder 19 is formed complementary to the shoulder 80 13 of the tubular stem. A spring 20 is coiled about the pin 18 and interposed between the shoulders 13 and 19. Two spiral grooves 21 are provided in the exterior of the reduced pin 18, and these grooves coact with 85 a pair of complementary lugs 22 located at diametrically opposite points in the open center of the rotatable head 5, and a cap 23 on this grooved extension retains the 90 grooved pin within the head.

By removing the bottom 2, the two compartments may be filled with the condiments, and then the bottom of course is threaded to closed position. When using the device, one condiment may be dispensed from the 95 holder when the latter is inverted, and then by pressing with the finger on the push pin 15, the cover or head 5 is oscillated or rotated through an arc of 180° bringing the perforated portion of the head beneath the other compartment of the holder, and when retained in this position the condiment may be dispensed as usual. When pressure is released from the push pin, the spring 20 automatically returns the rotatable head 5 100 to normal position.

Having thus fully described my invention, what I claim as new and desire to secure by Letters Patent is:—

1. The combination in a condiment holder 110 having a pair of interior compartments and an exterior annular flange forming a

groove of a head rotatable in the groove and provided with a perforated portion, a tubular stem within the holder, a spring pressed plunger longitudinally reciprocable in the 5 stem, and co-acting means on the head and plunger for rotating the head.

2. In a condiment holder having a rotatable head and a perforated portion therein, the combination with a partition forming

separated compartments, of a tubular stem 10 in the partition, a plunger in the stem, a reduced extension on the plunger having a spiral groove, an exterior retaining cap on the extension, and a guide lug on the rotatable head for co-action with the groove. 15

In testimony whereof I affix my signature.

ALBERT STEINER.
